UNITED STATES PATENT OFFICE.

FRANCIS HARLEY DAVIS, OF MONTEREY, CALIFORNIA.

HIGH-SPEED ROTARY DRILLING MACHINE.

Application filed June 12, 1923. Serial No. 44,914.

To all whom it may concern:

Be it known that I, FRANCIS HARLEY DAVIS, citizen of the United States, residing at Monterey, in the county of Monterey and State of California, have invented certain new and useful Improvements in High-Speed Rotary Drilling Machines, of which the following is a specification.

My invention relates to improvements in high speed rotary drilling machines for boring into the earth's strata, for mineral exploration, making wells, soundings, concrete testings and for such other purposes as a machine of this kind can be used. My drilling machine is primarily designed to operate a shot drill but can be used to operate other rotating types of drills.

My invention consists in an improved form of drill-gate which supports feed-guides; in the provision of a feed-carriage; in the provision of an improved form of drill feed; in a new and improved means of affording access to the borehole for large tools or casing; in a novel construction of hoist in relation to its drum-shaft and an interior drive-shaft passing therethrough and in certain other details of construction and combinations of parts as will hereinafter be fully set forth.

The objects of my invention are to provide a high speed drill that will do faster drilling, that will reduce the cost of construction of such drills, reduce cost of upkeep, save time and labor while drilling and, generally to improve the construction and operation of drills of this type.

I attain these objects by the mechanism illustrated in the accompanying drawing in which:

Figure 1, represents a front view of a drilling machine embodying my invention; Figure 2, a cutaway top view of the machine; Figure 3, a vertical section of the machine on the line A—B of Figure 1; Figure 4, a vertical detail section of the machine on the line C—D of Fig. 1; Fig. 5, a detailed view on the line E—F of Figure 2; Fig. 6, a rear view of swivelling member; Fig. 7, top view of swivelling member; Fig. 8, rear view of the gate 2; Fig. 9, general view of machine on line A—B on a little larger scale; Fig. 10, detail elevation of a modified form of feed carriage; Fig. 11, sectional detail of the feed carriage on the line G—H of Figure 10. Like characters of reference designate simi-

lar parts throughout the different figures of the drawing.

Apart from the details of the feed carriage and feed mechanism the drill herein illustrated comprises three frame members; namely, a stationary supporting member 1 and two other members carried thereby and relatively movable to the said supporting member and to each other. The stationary member supports bearings for a hoisting drum and bearings for a drive shaft and means for holding the drive shaft in and out of its operating position. One relatively movable member, namely the gate 2 carries bearings for mounting a drill-spindle, together with feed guides and feed yokes slidably mounted thereon; the other relatively movable member, the swivel-plate 47 Fig. 6, is interposed between the stationary supporting frame and the gate 2, its function being to incline the drill-spindle for drilling at different angles. The function of the gate 2 is to carry away the drill-spindle and all the feed mechanism from their operative position over the borehole so that access may be gained thereto.

The stationary supporting member or drill frame, herein designated by the reference character 1, is furnished with a plurality of bolts 48 and a cylindrical groove 50 adapted to engage with its counterpart, the guide-rib 49. The swivel-plate 47 shown in Fig. 6, on its rear face has a cylindrical guide-rib 49 adapted to fit into groove 50 to maintain correct axial alignment between the two members, the arcuate bolt-slots 51 being concentric with guide-rib 49 enable said swivel-plate to be fastened rigidly to the frame 1 at any desired angle to the vertical by the bolts 48. The swivel-plate is further furnished with a hole 52 through it, said hole being larger in diameter than the diameter of pinion 3, at one end it is provided with a hinge member 21 while the opposite end is provided with a slot and lugs for a latch-bolt 12, on the front face of said swivel-plate are two vertical slotted grooves 24 and 24'. The gate 2 is provided with a hole 52 through it similar to hole 52 of swivel-plate, also has the hinge complement of that of the swivel-plate so that the two may be hinged together by means of a bolt. The inner surface of gate 2 is provided with the tongued ribs 23 and 23' adapted to intermesh with grooves 24 and 24' of swivel-plate. Both members are

hinged to each other at 21. Gate 2 is securely locked to the swivel-plate by the latch-bolts 12 carried by the swivel-plate and engaging with the bolt-slots 12' of the gate, 5 when the gate is thus bolted to the swivel-plate by the latch-bolts 12 and the swivel-plate securely bolted to the supporting frame by the bolts 48, both gate and swivel-plate become in effect an integral part of 10 the said supporting frame.

The drill-spindle 10 has the bearings 36 and 36' and the usual long grooves 37 and 37' diametrically opposed extending along its length and adapted to cooperate with 15 the splines 38 and 38' attached to the driven gear 4 so as to permit longitudinal movement of the said drill spindle in either direction for the full length of its travel between the bearings 36 and 36' and the thrust 20 bearings 16 and 15 respectively either while stationary as regards revolution or while receiving continuous revoluble movement through the intermeshing gears 3 and 4 (clearly depicted in Fig. 3) and imparted 25 from drive shaft 9 driven by the belt pulley 39 or any suitable means, said pulley is provided with spline engagement on the shaft 9 for a purpose appearing hereinafter.

Further reference to Fig. 1 shows the 30 feed-guides 25 and 25' rigidly supported by the gate 2 in their socket bearings 40 and 40' and held in place therein by the set screws 17, 18, 19, and 20. The feed-yokes 13 and 14 are adapted for slidable engagement with 35 the feed-guides 25 and 25' and to act therewith as supplemental bearings for the drill-spindle 10, the said drill-spindle is provided with the thrust bearings 15 and 16 co-acting with the inner faces of the said feed-yokes 40 and is revolvably mounted in the said feed yokes in such manner that a movement of the feed yokes in either direction longitudinally would impart thrust from the said feed yokes to the drill-spindle and cause it 45 to slide through the driven gear.

The combination of parts comprised in the drill-spindle, thrust bearing and feed-yokes, regarded as a unit, form a feed-carriage and may be referred to as such hereinafter; however, in Figs. 10 and 11 I show as a modification of the principle involved, a feed-carriage cast in one solid piece. As shown in Figs. 10 and 11, the feed carriage has no flexible members but is adapted to be 50 moved in either direction longitudinally of the feed-guides 25 and 25' by rack and pinion means, the pinions 25^a are keyed fast to the winding-shaft 27 and engage with the cogged teeth of the rack members 25^b shown 55 on the outer edges of the longitudinal side-bars of the carriage. Winding-shaft 27 is adapted to be turned in either direction clock-wise or counter clock-wise by means of the worm wheel 29, the worm 30 and worm-handle 31, as shown.

It is obvious that such a feed-carriage can be caused to move longitudinally of the feed-guides by various means such as a screw, a rope, or a rack and pinion means. A preferable form of actuating my feed-carriage for imparting upward or downward movement of the drill is by chains two of which roll up on sprockets or drums while the two opposite chains unroll therefrom simultaneously. The worm wheel 29, worm 30 and worm handle 31 (Figs. 1 and 2) constitute a manually operated means of turning the winding shaft 27 on which between the bearings 28 and 28' are keyed to the said shaft four sprocket wheels the two outer 70 designated 32 and 32' and the two inner, 33 and 33'. The said winding shaft 27 lies in a plane parallel with the feed-yokes 13 and 14. Feed-yoke 13 is provided with the lugs 34 and 34' (or other suitable means of attaching a sprocket chain thereto). The point of attachment is axially in line with the centres of the feed-guides 25 and 25' and the center of the drill-spindle 10. Yoke 14 is similarly furnished with the lugs 35 and 35'. 90 The pitch line of all four sprocket wheels is precisely in line with the lugs 34 and 34' of feed-yoke 13 and lugs 35 and 35' of feed-yoke 14. The sprocket-wheels 32 and 32' and 33 and 33' are furnished with the sprocket chains 41 and 41' and 42 and 42', one pair of chains is adapted to be wound in one direction and the other pair in the opposite direction as shown in Fig. 4. From the illustration it will be seen that motion of the worm-handle 31 in one direction would impart motion to the feed-carriage in one direction and that a reverse motion of handle 31 would move the feed-carriage in the opposite direction, one pair of chains winding 105 on the sprocket and the other pair unwinding simultaneously according to the direction of the winding of handle 31, but all four chains pull equally on the feed-yoke and in a true axial line with the feed-guides no matter what the direction of the winding may be. This novel form of drill feed gives instant and precise control of the drill feed in either direction but if a considerable quick drawback of the drill is required the spring 110 jaw-clutch 43 can be instantly released thus disengaging the winding mechanism from the shaft 27 allowing the same to revolve freely within the worm-wheel 29 thus enabling the drill to be pulled off the bottom by means of a rope and hook which may be attached to the bale 44 until the bearings 16 and 36' come together.

I am aware that various forms of guides have been used for drill-spindles located at points above the point of drive (the gears) for steadyng the drill-spindle against wobbling when high above the gears as is the case when the drill-spindle has been raised to its highest limit preparatory to drilling 125 130

down a fresh portion of the sectional drill-
rods, but, the steadyng effect of such guides
above the gears is variable and their ef-
ficiency wanes as the drill-spindle travels
5 down them in the process of drilling; fur-
thermore, such guides located above the
point of drive, by reason of their location
at the upper end of the drill-spindle fail to
steady the drill-spindle and gears against
10 certain, violent vibrations and shocks that
come up the drill rods out of the bore-hole
as hereinafter explained, whereas, the feed-
carriage of my invention does do so, the
drill-spindle being at all times uniformly
15 braced against flexure and vibrations
throughout its entire range of travel. More-
over, the feed-guides 25 and 25' when re-
ceiving shocks and vibrations transmitted
thereto by the feed yokes 13 and 14, function
20 in a new way by each feed-guide yielding its
modulus or moment of elasticity which
tends to absorb such vibrations so that they
die down before ever entering the gears.

I have proved by practice that under cer-
tain conditions it is very desirable to re-
volve a drill rapidly. In one instance, while
drilling a 5" hole (five inch) hole in hard
sandstone I was able to drill six feet an hour
30 with the drill revolving two hundred revolu-
tions per minute, stopping the drill three
times to add two foot lengths of additional
drill-rods. By speeding up the drill to more
than six hundred revolutions per minute I
drilled twelve feet of the same rock under
35 the same conditions in less than an hour and
had to stop six times to add two foot rods.
I found that while increasing the speed of
rotation from a medium to a fast speed a
point was reached where the drill-rod down
40 the hole lashed and vibrated so alarmingly
as to threaten to wreck the machine but that
on still further increasing the speed of ro-
tation the rods straightened themselves in
the hole, a gyratory action was induced in
45 them, the drill was relieved of excessive
friction against the wall of the hole which
enabled me to do the remarkably fast drill-
ing above mentioned. By the use of my
feed-carriage I am enabled to attain still
50 higher speeds of rotation of the drill with
perfect ease and safety, and do still faster
drilling.

In drills of the rotary type wherein the
well known form of rotator is used for re-
volving the drill the said rotators are
55 generally made with an opening through
their centers large enough to admit of cas-
ing or tools of large size to be passed through
them, but in drills of the type of construc-
tion resembling the subject of my improve-
60 ment, which might be called the diamond
drill type, wherein a string of drill-rods is
rotated by means of a drill-spindle, or man-
drel, it has been largely the practice to use
65 a hinged member such as the gate 2 of this

specification to carry the drill-spindle away
from the bore-hole when handling tools in
or out of the same, the drill-spindle first
being unscrewed from the drill-rods; this
serves the purpose where casing or tools of
70 small diameter are used but it frequently
occurs that formations are met with when
drilling that cave in and call for casing, and
frequently casing after casing is called for
in order to reach the objective point of the
75 bore-hole and unless such boreholes are com-
menced with casing of large diameter there
is danger of the borehole having to be re-
duced to the smallest diameter before reach-
ing the desired depth, numberless bore-
80 holes have had to be abandoned from this
cause.

In order to enable drilling machines of
this type to use fairly large casing or drill-
ing tools, various forms of construction have
been adopted, some of which operate in con-
junction with a gate, and some without.
In many types of diamond drills provision
has been made for racking the whole drill-
ing machine back from the borehole when
access was required thereto,—and frequently
these machines weigh thousands of pounds,
I cite these examples for comparison with
my simple, inexpensive, labor-saving and ef-
ficient means whereby room, and to spare,
90 is provided for the largest tools or casing
to have access to the borehole, simply by
swinging open the gate 2, thus carrying
away everything from over borehole 11 ex-
cept the pinion 3 and a small portion of
95 shaft 9 carrying said pinion 3, both of which
may be removed from this overhanging posi-
tion with respect to the borehole, by lifting
the latch 5 as shown in dotted lines in Fig. 5
and operating the shift-lever 55 in a direc-
100 tion away from the borehole which causes
the shaft 9 to be retracted from its operative
position by sliding in its bearings 7 and 8
until latch 5 can be dropped on the opposite
side of thrust-collar 6, which leaves the ar-
105 rangement of parts as illustrated in Fig. 2
wherein the borehole is shown uncovered.
The lugs 45 constitute a convenient means of
keeping pulley 39 in position while shifting
the shaft with pinion 3 from the operative
110 to the inoperative position.

I desire it understood that while the re-
tractable drive-shaft 9 is herein shown in
combination with my feed-carriage, feeding
means, I also consider the said retractable
drive-shaft 9 as an independent entity and
120 wish so to protect it by this specification that
it may be covered in its use in any kind of
drilling machine to which it may be adapted.

Figure 9 shows hoisting-drum 46 mount-
ed on the hollow drum-shaft 53 and carried
in the independent bearings 54 and 54' with
drive shaft 9 running therethrough, concen-
tric therewith, but not in contact with each
other there being a space between the inte-
125 130

rior of 53 and the exterior of 9 which novel construction in this connection admits of heavy strains being applied to hoist 46 without danger of binding drive-shaft 9. This construction ensures that said shaft 9 may be shipped to or fro in the bearings 7 and 8, freely, without binding from the pull of the hoist.

While I have herein shown and described 10 specific forms of my invention I do not wish to be limited thereto except by such limitations as the claims may import.

I claim—

1. In a drill of the kind described, a stationary supporting structure and a drill-head carried thereby, free-ended vibratable feed-guides fixedly carried by the drill-head, independent spindle-carrying means, said means freely mounted on the vibratable feed-guides and adaptable for straight up and down line of travel thereon, said spindle-carrying means provided with suitable feed element or elements engaging complementary element or elements carried by the 25 drill-head, said engaging elements constituting a direction-changing means being adapted to impart regulative adjustment to the said spindle-carrying means longitudinally of the said vibratable feed-guides.
2. In a drill of the kind described, a stationary supporting structure carrying a

drill-head provided with a gate, the gate carrying free-ended vibratable feed-guides, independent spindle-carrying means freely engaging the said feed-guides and being adapted for up and down movement longitudinally therewith, said spindle-carrying means being provided with suitable feed element or elements engaging complementary element or elements carried by the drill-head, said engaging elements constituting a direction-changing means being adapted to impart regulative adjustment to the said spindle-carrying means longitudinally of the said vibratable feed-guides. 40

3. In a drill of the kind described, the combination with a stationary supporting structure and a drive-shaft whose bearings are stationary with said stationary structure, said drive shaft adapted for movement both rotary and longitudinally in a straight to and fro line of travel in its bearings, of a hoisting drum, means for driving same, hollow drum-shaft for said drum, said drum and drum-shaft enveloping but not touching said drive-shaft, bearings for drum-shaft situated between the bearings for drive-shaft substantially as described and for the purpose set forth. 55

In testimony whereof I affix my signature.

FRANCIS H. DAVIS.
